UNITED STATES PATENT OFFICE

LEOPOLD STERNBERGER, OF PHILADELPHIA, PENNSYLVANIA.

WASHING-MACHINE.

SPECIFICATION forming part of Letters Patent No. 234,438, dated November 16, 1880.

Application filed October 7, 1879.

To all whom it may concern:

Be it known that I, LEOPOLD STERNBERGER, of the city and county of Philadelphia, in the State of Pennsylvania, have invented 5 certain new and useful Improvements in Washing-Machines, of which improvements the following is a specification.

My invention relates to machines designed to operate by power for washing materials or 10 garments in quantities in manufacturing establishments, and is an improvement upon that for which Letters Patent of the United States No. 192,027 were granted and issued to me under date of June 12, 1877. 15 The objects of my present invention are to provide improved means of constructing the rotating washing-vessel and maintaining the same in true cylindrical form, and to furnish a simple and effective means of opening and 20 closing the water-discharge valves during the rotation of the vessel.

To this end my improvements consist, first, in combining, in a washing-vessel, a series of abutting staves, forming a cylindrical body, 25 with metallic end supporting-rings and a series of sector-shaped heads; secondly, in combining a washing-vessel so constructed and adapted to rotate upon a central shaft with a wheel secured upon said shaft adjacent to 30 one end of the vessel, said wheel having a ring formed upon its periphery, which supports the staves of the cylindrical body, and having a driving-gear and a brake-drum formed or secured upon it; thirdly, in combining with said 35 rotative cylindrical washing - vessel certain sliding valves covering openings therein, and valve-operating devices capable of being varied in position, whereby the valves may be moved in either direction during the rotation 40 of the washing-vessel; and, fourthly, in the combination of parts constituting the variable valve-operating mechanism, all as more fully explained in the following description.

The improvements claimed are hereinafter 45 fully set forth.

In the accompanying drawings, Figure 1 is an end view, in elevation, of a washing-machine embodying my improvements; Fig. 2, a similar view of the washing-vessel, taken from 50 the opposite end; Fig. 3, a side view, in elevation, of the machine; Fig. 4, a perspective

view of the devices for operating the brake and belt-shifter; Figs. 5 and 6, sectional views, showing the end supporting-rings of the washing-vessel; and Fig. 7, a plan view of one of 55 the water-discharge valves with its seat and guide.

The washing-vessel A is composed of a series of tongued-and-grooved staves, *a*, abutting so as to be united into cylindrical form 60 and bound together by hoops *a'*. The ends of the vessel are closed by heads formed of a series of sector-shaped pieces of wood, *a²*, and the vessel is secured upon a shaft, B, which rotates in suitable bearings in a frame, B'. 65 The interior of the vessel A is divided by a series of slatted partitions into radial compartments (in this instance four in number) in a similar manner to the vessel described and shown in my Letters Patent No. 192,027 afore- 70 said; but as such internal construction constitutes no part of my present invention it need not be here particularly set forth.

In order to prevent changes of form in the vessel, resultant upon the expansion and contraction of the pieces *a²*, forming its heads, I interpose between the head-pieces *a²* and the staves *a*, at each end of the vessel, a metallic supporting-ring, which is turned into truly circular form and let into a groove cut in the inner faces of the staves. The latter rest upon the outer surfaces of the rings and are bound thereto by the hoops *a'*. The supporting-ring C', at the end of the vessel nearest the driving mechanism, is preferably formed upon the 80 periphery of a wheel, C, which carries a brake drum or rim, C², and has secured upon it a spur-gear, C³, through which rotation is imparted to the vessel A from a pinion, d, on a counter-shaft, D, driven from the prime mover, 90 as presently to be described. The supporting-ring C⁴, at the opposite end of the vessel, is formed as shown in section in Fig. 5, and an outer ring, e, is secured upon it, so as to form a circular recess, which acts as a guide for the 95 outer edges of the sliding doors J, which close the end openings of the several compartments of the vessel. Each of the end supporting-rings fits within a recess in the staves, and the end pieces of the adjacent head bear against 100 and cover its inner face, so that access of the clothes or material within the vessel to the

surface of the ring is avoided, while the ring serves to sustain the staves which bear against its outer face, and consequently prevents the distortion of the vessel from its normal cylindrical form, which tends to ensue where the staves are supported, as heretofore, only by the wooden head-sections.

The counter-shaft D, by which the vessel A is driven, carries a fast pulley, D', and a loose pulley, D'', and a driving-belt from a main or line shaft is shifted from the loose to the fast pulley, or vice versa, according as it is desired to rotate or to stop the movement of the vessel, by shifting-arms e, secured upon a bar, E, which slides in guides e' upon the frame of the machine, and is operated simultaneously with a friction-band, F, encircling the brake-rim C² of the wheel C, by a sliding bar or rod, E', which is connected at one end by a bell-crank, e², with the bar E, and is provided at the other end with a proper handle or lever, by which it may be moved. In the instance shown the end opposite that to which the bar E is connected is coupled by a bell-crank, e³, with a bar or rod, e⁴, having a handle upon its opposite end, and which may, if desired, have a segment-lever and catches for holding it in desired position, the object of employing the bar e⁴ being, for the sake of convenience, to enable the operator to start and stop the machine from the end adjacent to which the valve-operating lever is located.

A pin, e⁵, upon the bar E' enters a slot in the upper end of one arm, e⁶, of a rock-shaft, e⁷, which is mounted in a bearing on the frame B' of the machine, and carries two arms, e⁸ e⁹, to which the ends of the friction-band F are respectively connected.

By the vibration of the rock-shaft, induced by the movement of the bar E' to the left in Fig. 1, (which movement shifts the driving-belt from the fast to the loose pulley,) the friction-band F is pressed against the face of the brake rim C², and the movement of the vessel A is arrested coincidently with the cessation of the application of driving-power to the counter-shaft D, and, conversely, the friction band is released from the brake-rim coincidently with the movement of the bar E' to the right to apply power to the counter-shaft.

The starting and stopping mechanisms, although here described for the better understanding of the entire machine, do not form a part of the improvement herein claimed, but are set forth and claimed in a separate application filed by me.

Water and solution of soap can be best supplied to the vessel A at one of its ends, as set forth in my Patent No. 192,027, before referred to, and for the purpose of drawing off water from the vessel from time to time, as may be required. Each of its compartments is provided with an opening covered by a plate, G, having a portion of its surface perforated, 65 grated, or provided with a screen or strainer,

which opening may be closed at pleasure by a valve, G', sliding longitudinally over the plate G between inclined or dovetailed guides G² formed on the sides thereof.

One of the guides G² is parallel to the line of movement of the valve G', and the other is slightly inclined thereto, a wedge or liner, g, the two sides of which are respectively parallel to the two guides, and which is longitudinally adjustable by means of bolts passing through slotted holes, being interposed between the valve G' and the inclined guide, so as to enable wear of the guides and valve to be taken up as required, and an easy movement of the valve without undue slackness to be assured.

A stud, g', carrying a friction-roller, g², projects from the face of each of the valves G', and the valves may be opened or closed, as desired, during the rotation of the vessel, by means of two cam-arms, H, each of which is pivoted to the frame of the machine adjacent to the path described by the studs g' in the revolution of the vessel A, and is curved longitudinally concentrically therewith and bent transversely outward at its free end, as shown in Fig. 3.

The cam-arms H are connected by a link, h, to which they are pivoted at the point in their length at which they are bent, so that their least distance apart shall be such as to allow the friction-rollers g² to pass easily between them, and the link h is, in turn, pivoted at its center to a horizontal bar, H', fitting in guides on the frame, and which may be moved longitudinally therein by a hand-lever, H², secured upon a rock-shaft, h', mounted in a bearing in the frame and carrying an arm, h², the upper end of which is connected to the bar H'.

The hand-lever H² may be held in any desired position by a segment, h³, and spring-detent h⁴, and, according to the greater or less range of movement imparted to it, the cam-arms H will proportionately move the valves G' by the contact of the friction-rollers g² with their inner surfaces in the rotation of the vessel A, the openings in the plates G remaining wholly or partially covered or uncovered, in accordance with the positions to which the valves are brought by any adjusted position of the cam-arms, until the valves are moved by a change in the position of the hand-lever and cam-arms. The inclination at which the cam-arms are bent may be greater or less, according as the valves are desired to be moved more or less quickly, and any desired degree of opening may be given by a corresponding adjustment of the hand-lever, the water escaping in accordance therewith from each of the grated or perforated plates as it in turn descends below the axis of the vessel A during the rotation thereof.

Each of the several compartments of the washing-vessel has an end opening, I, through which the material to be washed is introduced and removed, and which is closed by a door,

J, sliding circumferentially over the head in which the opening is formed between guides, one of which is formed by the supporting-ring C⁴ and the outer ring, c, and the other by a flanged ring, c', secured upon the head or upon the shaft of the vessel. Each door, when closed, is held firmly in position by radial bolts K, sliding in guides or staples k upon the door and entering staples k' upon the rings c and c', respectively. The bolts K are moved into and out of the staples k' by crank-disks k², pivoted upon the doors, between and in line with the bolts, and to which the latter are connected by links k³. The crank-disks may be vibrated by means of handles, or by a proper wrench or spanner fitting over projections formed upon them, and to guard against any unauthorized access to the compartments of the vessel A the bolts of each of the doors are, when the door is closed, secured in position by a lock, k⁴, which prevents such movement of the crank-disk as would admit of the withdrawal of the bolts from the staples k'.

I claim as my invention and desire to secure by Letters Patent—

1. The combination, in a washing vessel, of a series of abutting staves forming a cylindrical body, a metallic supporting-ring fitting into a groove formed in the inner surface of the cylindrical body adjacent to each of its ends, and heads composed of a series of sector-shaped pieces, each of which abuts at its outer end against the inner surface of one of the sup-

porting-rings, substantially as and for the purposes set forth. 35

2. The combination of a cylindrical washing-vessel the body of which is composed of a series of abutting staves, and which is secured to and rotates with a central shaft, and a wheel secured upon said shaft adjacent to one end 40 of the vessel, said wheel having a ring formed upon its periphery, which supports the staves of the cylindrical body, and having a driving gear and a brake-drum formed or secured upon it, substantially as set forth. 45

3. The combination of the rotating cylindrical washing-vessel, sliding valves which cover openings therein and are each provided with a stud projecting radially from the vessel, two pivoted cam-arms, between which the valve-50 studs pass in the rotation of the vessel, and a sliding arm by which the cam-arms may be varied in position so as to move the valves in either direction during the rotation of the washing-vessel, substantially as set forth. 55

4. The combination of the pivoted cam-arms, the link connecting said arms, the sliding bar pivoted to said link, the hand-lever for operating said sliding bar, and the segment and spring-detent for regulating the position of 60 the hand-lever, substantially as set forth.

LEOPOLD STERNBERGER.
